UNITED STATES PATENT OFFICE.

THOMAS H. BLAIR, OF NORTHBORO, MASSACHUSETTS, ASSIGNOR, BY MESNE ASSIGNMENTS, TO BLAIR LIGHT COMPANY, OF NORTHBORO, MASSACHUSETTS, A CORPORATION OF MASSACHUSETTS.

HYDROCARBON-LAMP.

No. 868,069.

Specification of Letters Patent.

Patented Oct. 15, 1907.

Application filed April 20, 1903, Serial No. 153,434.

To all whom it may concern:

Be it known that I, THOMAS H. BLAIR, a citizen of the United States, residing at Northboro, in the county of Worcester and State of Massachusetts, have invented 5 a new and useful Hydrocarbon-Lamp, of which the following is a specification.

This invention relates to that class of lamps which use gasoline or other fuel which is first converted into vapor and then mixed with air before it is burned.

10 The especial object of this invention is to provide an improved valve and means for operating the same to automatically control the feed of oil, to provide means for automatically preventing excessive pressures from causing the lamp to explode or be injured, said devices 15 comprising a cut out intended to extinguish the lamp whenever an abnormal pressure is generated, and also comprising a safety blow-out for automatically venting the pressure when the same exceeds a desired limit; and to provide for automatically extinguishing the 20 light after the lapse of any desired period of time.

To these ends, this invention consists of the hydro-carbon lamp, its attachments, and the combinations of parts as hereinafter described and more particularly pointed out in the claims at the end of this 25 specification.

In the accompanying three sheets of drawings, Figure 1 is a side view partially broken away of a hydro-carbon lamp constructed according to this invention. Fig. 2 is a perspective view illustrating the operation of the 30 shutter for automatically extinguishing the lamp after the lapse of any desired period of time. Fig. 3 is a perspective view of the connections for extinguishing the lamp when abnormal pressures are generated. Fig. 4 is a detail sectional view showing a safety blow-out arranged in connection with the filling tube. Fig. 5 is a 35 perspective view of the parts illustrated in Fig. 4. Fig. 6 is an enlarged view partially broken away of the turn-plug and its nipple. Fig. 7 is a side view of a lamp partially broken away illustrating a modified construction for operating the turn-plug. Fig. 8 is an enlarged 40 detail view of the parts illustrated in Fig. 7. Fig. 9 is a fragmentary view illustrating a modified construction for operating the swinging nipple, and Fig. 10 is a sectional view of the flattened pipe illustrated in Fig. 9.

45 In a previous United States Patent No. 700,475 granted May 20, 1902, a hydro-carbon lamp is described and claimed in which the pressure generated in the vaporizing coil automatically controls the oil supply fed into the vaporizer. In the actual manufacture of lamps 50 embodying this principle, the flow of oil into the vaporizer has heretofore been controlled by a needle valve. These valves have been found to operate efficiently when properly adjusted, and when the gasoline or fuel is free from impurities. In some cases, however, needle 55 shut-off valves cannot be used to advantage on account

of their liability to become clogged or not to seat themselves properly.

One object of the present invention is to arrange the regulating devices of the class to which this invention relates so that they may operate small turn-plug valves 60 while further objects of this invention are to provide safety cut-out devices for preventing the lamp from exploding if the automatic regulator should fail to work, or if for any reason abnormal pressure should be generated; and also to provide a lamp of this class with a 65 time controlled cut-out for extinguishing the lamp after the lapse of any desired period of time.

Referring to the accompanying drawings and in detail, A designates the cap or cover which incloses the working part of the lamp, and which is supported by 70 the ordinary fork B.

Extending down from the cap A is the globe G which incloses the burner of the lamp.

The operative parts of the lamp as herein illustrated, comprise an annular gasoline tank or fuel reservoir 10 75 from which the oil passes down through the regulating valve 12 through the pipe 11, up through the vaporizing coil to a header 13. The header 13 is connected by a pipe 14 to the inlet or filling pipe 15 so that the vaporizing pressure will be admitted to the fuel reservoir, 80 and is also connected by a return bend or trap pipe to the injector pipe 16.

Pivottally mounted in the lower end of the injector pipe 16 is a turn-plug 17 carrying the nipple 18.

The turn-plug 17 and its nipple 18 are most clearly 85 illustrated in Fig. 6. As shown in this figure, the turn-plug 17 is slotted or grooved around a portion only of its periphery, so that when said turn-plug is turned or shifted from its normal position it will act as a shut-off valve, cutting off the supply of fuel which normally 90 escapes through the nipple 18.

As shown in Fig. 1, the nipple 18 normally points down into the mixing tube 19 in which the gasoline vapor is mixed with a sufficient supply of air so that the same will burn properly in the burner, indicated by 95 dotted lines. In practice the hole through the nipple 18 is drilled with an exceedingly fine drill, and in order to insure the efficient operation of a lamp of this kind, a frequent inspection, and in some cases, renewal of the nipple is requisite.

One especial object in mounting the nipple 18 upon the turn-plug 17 is to provide a swinging support for the nipple which will permit the nipple to be swung or to be turned up by hand in position to be readily inspected and cleaned out when required. Access to 105 these parts for this purpose may be furnished through a small door or opening in the hood A. A further object in mounting the nipple 18 so that it can be swung or turned is to provide for cutting out and extinguishing the lamp when desired by turning the nozzle or nipple 110

18, so that its supply of vapor will not pass down into the mixing tube 19 but will be directed to one side thereof, cutting off the supply of fuel and extinguishing the lamp. The turning or swinging of the nipple is automatically controlled by the pressure generated in the lamp either through a diaphragm or otherwise as hereinafter described.

As illustrated in Figs. 1 and 3, a diaphragm 28 may be mounted in the diaphragm casing 27 and connected 10 to operate a lever 29 having a chain flexibly connecting the same with the turn-plug 17.

Engaging the lever 29, as shown in Fig. 3, is a spring arm or regulator 31, which is arranged to normally hold the lever 29 in its lowest position, but which is forced 15 back and releases the lever 29 when abnormal pressures are exerted upon the diaphragm 28. That is to say, in this construction instead of depending upon a gradual movement and a throttling action, the forcing back of the spring arm 31 will unlock or release the diaphragm, 20 so that the swinging nipple will be thrown quickly to one side and the lamp extinguished. During the normal operation of the lamp, however, the cut-out device will not be brought into operation, the action of the lamp being controlled by the automatic regulation of 25 the feed of the oil to the vaporizer.

As shown in Fig. 1, the turn-plug valve 12 is connected to be operated by a rod 20 having a spring coiled thereon for normally holding the valve open. The rod 20 is connected at its upper end to be operated 30 by a diaphragm inclosed in a diaphragm casing 21, which diaphragm casing is connected with the oil tank or reservoir 10. The action of this automatic regulating mechanism is substantially the same as the construction disclosed in said prior patent No. 700,475, 35 except that the supply is throttled by a turn-plug valve instead of the pointed or needle valves described in said prior patent.

As an additional means for preventing the possibility of explosion or the escape of liquid gasoline, a blow-out 40 is provided which will exhaust the pressure from the upper part of the gasoline tank whenever dangerous pressure is exerted therein. This blow-out may be combined with the filling tube and is illustrated most clearly in Figs. 4 and 5. As shown in these figures, the 45 filling tube 15 has a removable cap or cover 22 which can be taken off to permit the gasoline to be poured into the tank or reservoir.

Threaded into the cap 22 is a nipple 23, and fitting on the nipple 23 so as to confine a flexible membrane 24 50 of comparatively weak material thereon is a perforated clamping thimble 25, which is held in place by the outside cap 26. In practice pieces 24 of comparatively heavy tin-foil have been used which will be capable of withstanding a pressure of about fifty pounds to the 55 square inch, but which will be perforated and broken if subjected to materially high pressures, and it has been found that this arrangement of parts forms an especially efficient, inexpensive and reliable automatic vent for an oil reservoir of a lamp of this class; 60 while the location of this safety blow-out in connection with the filling tube insures an inspection of the same whenever the gasoline tank or reservoir is refilled and the parts are so combined that new pieces of tin-foil or other frangible material may be put in place.

65 Lamps of the class to which this invention relates

are now quite extensively employed for street lighting purposes, and are especially adapted for use in outlying or suburban regions where electric lamps or other means of illumination are not available. In suburban street lighting it is not requisite that the 70 lamps should burn through the entire night, and it is desirable that the lamps should be automatically extinguished when they have burned the required length of time. In practice this has heretofore been accomplished by limiting the capacity of the gasoline 75 tank or reservoir, so that the lamp would not burn over certain lengths of time. This is comparatively unreliable, and the same has also been found to be objectionable as such lamps are required to burn for longer periods during certain seasons of the year, or for other 80 reasons.

A further object of this invention is to provide time controlled extinguishing connections for extinguishing a lamp of the class referred to after the lapse of 85 any desired time.

As shown in Fig. 1, W designates a small clock which may be of the ordinary alarm clock type or other ordinary time piece.

The connections controlled from the clock W are most clearly illustrated in Fig. 2. Referring to this 90 figure, 32 designates the hour shaft which may be extended down from the clock W. Secured on the shaft 32 is a notched disk 33. Coöperating with the notched disk 33 is an arm 34, carried by a spring-pressed shaft 35. Extending from the lower end of the shaft 35 is 95 an arm 36 carrying a shut-off plate or a shutter 37 arranged to swing between the nipple 18 and the mixing tube 19. By means of this construction, when the notch in the disk 33 comes into engagement with the arm 34, the shutter 37 will be permitted to swing 100 into place beneath the nipple, deflecting the supply of gasoline from the mixing tube and extinguishing the lamp.

Many changes may be made in practicing this invention by those who are skilled in the art; for example, the last sheet of drawings illustrates two different ways in which the swinging nozzle may be automatically operated.

As shown in Fig. 7, the cap or hood A, the globe G which incloses the burner, the mixing tube 19 for 110 supplying a mixture of air and gasoline to the burner, may be of the same construction as before described. The injector pipe may be inclosed within a protective casing 82, and is provided at its lower end with a turn-plug section 81 carrying the nipple 83. The 115 turn-plug section 81 may correspond substantially with the turn-plug section 17 before referred to, except that the same is not intended to operate as a shut-off valve. Coöperating with the turn-plug section 81 is a lever 84 which may be operated by a diaphragm 120 85. In the use of this construction, the tipping or tilting of the nipple will not stop the flow of gasoline through the nipple, but will change its direction or deflect the same, so that it will not be fed down through the mixing tube 19.

Figs. 9 and 10 illustrate a still further modification of the means for operating the swinging nipple. In this construction, the injector pipe 16 is connected with a coil of pipe 86, which coil of pipe is of a flattened or non-circular cross section, as illustrated in 130

- Fig. 10. The end of the coil 86 normally points down into the mixing tube 19, and is provided with a nipple 87 having a wire or pin 88 which may be used to swing or turn the nipple up when the same is to be inspected.
- 5 The operation of this coil of flattened pipe is substantially the same as the so-called Flemish coil employed for pressure gages. That is to say, an abnormal increase of pressure will tend to straighten the coil so that the nipple 87 will be swung or turned from its 10 normal position.

I am aware that certain features of my invention may be used in different locations and in different combinations from that herein shown and described, for example, either a special automatic regulator, or 15 the swinging needle, or the time controlled cut-out, or the blow-out for automatically operating the lamp may be applied and used on different structures, or certain ones of said features may be omitted. I do not wish, therefore, to be limited to the special constructions I have herein shown and described, but 20

What I do claim and desire to secure by Letters Patent of the United States is:

1. In a hydro-carbon lamp, the combination of an oil tank, a vaporizer connected to receive oil therefrom, a 25 mixing tube for mixing the vaporized oil with air, a burner arranged to be fed by the mixed vapor and heating said vaporizer, a turn-plug regulating valve controlling the flow of oil from the tank into the vaporizer, and regulating mechanism for said valve controlled by the varying 30 pressure in the vaporizer for turning said plug to increase the flow as the pressure falls and to diminish the flow as the pressure increases, the turn-plug and the regulating mechanism being located exterior to the oil tank.
2. In a hydro-carbon lamp, the combination of a vaporizer, a mixing tube, a swinging nipple normally directing a supply of vapor from the vaporizer into the mixing tube, and connections for automatically swinging the nipple out of line with the vaporizer to extinguish the lamp. 35
3. In a hydro-carbon lamp, the combination of a vaporizer, a mixing tube, a swinging nipple normally directing its supply of vapor from the vaporizer into the mixing tube, and means controlled by vaporizer pressure for automatically swinging said nipple out of line with the mixing tube to extinguish the lamp when the vaporizer pressure rises above a desired limit. 40

4. In a hydro-carbon lamp, the combination of an oil tank, a vaporizer connected to receive oil therefrom, a mixing tube, a swinging nipple directing its supply of vapor from the vaporizer into the mixing tube, a burner 50 supplied from the mixing tube and arranged to heat the vaporizer, and a diaphragm acted upon by pressure in the oil tank and connected to turn the nipple out of line with the mixing tube when the oil tank pressure exceeds a desired limit.

5. In a hydro-carbon lamp, the combination of an oil tank, a vaporizer supplied therefrom, a mixing tube, a nipple directing its supply of vapor into the mixing tube, a burner connected with the mixing tube and arranged to heat the vaporizer, a diaphragm acted upon by oil tank 55 pressure, and a flexible connection between the diaphragm and nipple for turning the nipple out of line with the mixing tube to extinguish the lamp when the vaporizer pressure exceeds a desired amount, and also permitting the nipple to be turned or swung to one side by hand for inspection or renewal.

6. In a hydro-carbon lamp, the combination of an oil tank, a vaporizer supplied therefrom, a mixing tube, a swinging nipple normally directing its supply of vapor into the mixing tube, a diaphragm connected to operate 70 the swinging nipple, and a spring detent for said diaphragm for holding the parts in normal position until the vaporizer pressure exceeds a desired limit.

7. In a hydro-carbon lamp, the combination of an oil tank, a vaporizer, a mixing tube, a nipple normally direct-

ing its supply of vapor into the mixing tube, a diaphragm 75 casing connected with the oil tank, a diaphragm mounted therein, a lever to be operated by said diaphragm, a flexible connection between the lever and the swinging nipple, and a spring detent engaging the lever to hold the diaphragm inoperative until the vaporizer pressure exceeds a 80 desired limit.

8. In a hydro-carbon lamp, the combination of an oil tank, a vaporizer supplied therefrom, a burner fed from the vaporizer and arranged to heat the vaporizer, a filling tube for the oil tank, a removable cap for the filling tube 85 provided with a nipple, a perforated thimble having a socket, a perforated cap removably attached to the nipple and adapted to clamp the socket of the thimble over the end of the nipple, and a frangible diaphragm held between the thimble and the nipple, and of sufficient thickness to 90 cause the socket of the thimble to fit tightly on the nipple.

9. In a hydro-carbon lamp, the combination of an oil tank, a filling tube therefor, a nipple for the filling tube, a perforated thimble having a socket adapted to set over end of the nipple, and a frangible diaphragm held between 95 attached to the nipple adapted to clamp the thimble on the nipple, and a frangible diaphragm held in place between the thimble and nipple, said diaphragm extending between the socket of the thimble and the outside of the nipple, whereby said thimble may be forced over the diaphragm 100 and nipple and held in place by friction.

10. The combination in a lamp, of a supply tank, a vaporizer, a burner, a valve under control of the pressure in the tank for regulating the flow of liquid therefrom to the vaporizer, and a supplementary quick-acting valve independent of the first, but also under control of the pressure in the tank, for controlling the flow of gas or vapor from the vaporizer to the burner. 105

11. The combination in a lamp, of a pressure tank, a burner, a vaporizer subjected to the heat of the burner, a valve under control of the pressure in the tank, for controlling the flow of liquid from the tank to the vaporizer, and a supplementary quick-acting valve independent of the first, but also under the control of the pressure in the tank, for controlling the flow of gas or vapor from the 110 vaporizer to the burner upon the attainment of an abnormal degree of pressure. 115

12. In a hydro-carbon lamp, the combination of an oil tank, a vaporizer fed therefrom, a mixing tube, a nipple connected with the vaporizer normally directing its supply 120 of vapor into the mixing tube, a shutter, and clock-controlled connections for interposing the shutter between the nipple and the mixing tube.

13. In a hydro-carbon lamp, the combination of an oil tank, a vaporizer, a mixing tube, a nipple connected with the vaporizer and normally directing its supply of vapor into the mixing tube, a spring-actuated shutter, a notched disk in operative connection with the shutter, and a clock mechanism to turn said disk, and to cause the shutter to be interposed between the nipple and the mixing tube at any 125 desired time.

14. The combination in a lamp, of a supply tank, a vaporizer, a burner, a valve under control of the pressure in the tank for regulating the flow of fluid therefrom to the vaporizer, and a supplementary valve independent of the first, but also under control of the pressure in the tank, for controlling the flow of gas or vapor from the vaporizer to 135 the burner.

15. The combination in a lamp, of a pressure tank, a burner, a vaporizer subjected to the heat of the burner, a valve under control of the pressure in the tank, for controlling the flow of fluid from the tank to the vaporizer, and a supplementary valve independent of the first, but also under the control of the pressure in the tank, for controlling the flow of gas or vapor from the vaporizer to 140 the burner. 145

In testimony whereof I have hereunto set my hand, in the presence of two subscribing witnesses.

THOMAS H. BLAIR.
